UNITED STATES PATENT OFFICE

2,492,067

ELECTRIC MICROMETER
SYSTEM

Henry C. Schildmeier, Indianapolis, Ind.

Application January 30, 1948, Serial No. 5,342

11 Claims. (Cl. 33—164)

1

This invention relates to a micrometer of the electric type.

The chief object of the present invention is to magnify a minute dimension departure and translate same into electrical energy, the variation in the electrical energy being readily measurable and readable upon an indicator such as a current meter (ammeter).

The chief feature of the present invention resides in the utilization of flux variation in a simple form of micrometer and measurement of such variation by suitable means, the flux varying structure being directly incorporated in a micrometer which may be of the portable type.

Heretofore in the art of measuring devices there has been provided an electromagnetic field in which an armature is movable and effects current variation which when magnified can be read upon an ammeter. Such micro-measuring devices are exceedingly expensive, usually of large size and not readily portable and above all are quite expensive as well as very delicate.

The present invention eliminates all these objections.

Other objects and features of the invention will be set forth more fully hereinafter.

The full nature of the invention will be understood from the accompanying drawings and the following description and claims.

In the drawings:

Fig. 1 is a top plan view of the micrometer portion of the invention.

Fig. 2 is a side elevation thereof.

Fig. 3 is a wiring diagram.

In Figs. 1 and 2 of the drawings, 10 indicates a tubular or like guide with extended channel portion 11 and foot 12. Slidably in said guide is a tubular member 13 mounting handle 14 at an exposed end. The other end, slidably in channel 11, mounts C-head 15 with bearing face or anvil 16. This tubular member is cut away at its top portion forming a channel nested, intermediate channel portion 17.

Adjacent the C-head are a pair spaced ears 18 and 19 of para-magnetic material. These ears are connected together as at 20 and suitably secured to the tubular member 13. Ears 18 and 19 with screw 19a and nut 18a secure one leg of a U-shaped laminated magnetic core 21 to said tubular member. Disposed about the other leg of said core is the coil 22 with leads 23 and 23a.

Slidably in both tubes is the rod 24 which may be tubular if desired. Herein one exposed end of the solid rod is threaded as at 25 to anchor knob

2

26. The opposite exposed end of said rod is threaded at 27 for an appreciable length. Thereon is threaded nut 28 and hammer head 29, the latter having a threaded socket 30 to take the threaded end 27 of said rod. Nut 28 locks the hammer to the rod in adjusted position. In the event of wear, the hammer may be replaced.

Carried by rod 24 at the portion exposed by tubes 10 and 13 is the para-magnetic base 31 having clips 32 with ends 32a and ears 33 associated with bolts and nut 34. Mounted thereby is the laminated magnetic U-shaped core 35, one arm being associated with the base and the other arm mounting a coil 36 having leads 37 and 37a.

Reference will now be had to Fig. 3. A pair of supply lines L1 and L2 are connected to the leads 23 and 23a of the coil 22. If desired a potentiometer 38 may be included in this circuit. A direct current milliammeter 39 may be connected through rectifier 40 to the leads 37 and 37a of coil 36. If desired, a potentiometer 41 may be included in this secondary circuit.

When the two cores 21 and 35 are in abutting relation the full flux relationship possible is attained. The potentiometer or potentiometers are adjusted to attain maximum needle deflection or ammeter indication. When the cores are slightly separated, the reluctance of the magnetic circuit increase and current value in the secondary decreases proportionately. Micro-measurable differences in air gap between cores produces comparable large signal indication differences. While these do not, over a wide range of linear unit differences, have corresponding unit differences in signal indications, the fact that decreasing secondary current values indicate increasing linear departures permits this simple device to be utilized for micro-measurement purposes.

For example, if the stock dimension required is 1.250 inches, the several parts of the device are adjusted so that 1.253 inches of distance between anvil 16 and hammer 29 produces approximately maximum needle deflection. Then a guage block of 1.250 inches is applied and the current value adjusted by the potentiometer or potentiometers so that the "zero" reading of the indicator needle reads unity or ten on the scale if the ammeter is of dual scale type. Then any 0.0001 inch departure from the critical dimension plus or minus in a thousandth of an inch will result in a reading of 1.1 or 0.9 on the unity scale respectively. Since the difference between 1.1 and 1.0 or 1.0 and 1.1 on the scale is provided with five, ten or twenty divisions, the actual linear distance departure from the required standard can be read-

ily and accurately determined. If the maximum tolerance is plus or minus two ten thousandths of an inch, it is readily indicated.

Undersize and oversize articles outside of the micro-tolerances can be readily detected and discarded. Of course, the oversize articles can be reduced and salvaged.

Herein an outside caliper type micrometer is illustrated. For measurement of holes and cavities an inside type caliper micrometer may be utilized and the undersize rejects reworked and salvaged.

While the invention has been illustrated and described in great detail in the drawings and foregoing description, the same is to be considered as illustrative and not restrictive in character.

The several modifications described herein as well as others which will readily suggest themselves to persons skilled in this art, all are considered to be within the broad scope of the invention, reference being had to the appended claims.

The invention claimed is:

1. A micro-micrometer structure having a pair of linearly separable elements for measuring, a pair of confronting coils each rigid with an element, a core for each coil having a pole face, the pair of pole faces confronting each other, the cores being substantially saturated at the required dimension, a current supply for one coil, and a current measuring device in the circuit of the other coil, movement of the indicator of the device from a predetermined selected maximum position indicating variation of the measured distance for the required dimension.

2. A micro-micrometer comprising an elongated member, a second elongated member, a U-shaped magnetic core magnetically insulated from and carried by each member, the core pole faces confronting each other, a coil carried by each core, a current supply for one coil, a current measuring device, and connections between the other coil and the device, relative movement of the members being indicated on the device.

3. A micrometer as defined by claim 2 where-in a potentiometer is in series with one of the coils.

4. A micrometer as defined by claim 2 where-in the current supply is of alternating current

49
50

type, and the current measuring device is of direct current type, and a rectifier is in series with the device.

5. A micrometer as defined by claim 4 where-in a potentiometer is in series with one of the coils.

6. A micrometer as defined by claim 4 where-in a potentiometer is in series with each coil.

7. A micrometer as defined by claim 2 where-in a potentiometer is in series with each coil.

8. A micro-micrometer having three approximately concentrically disposed elongated members, the outermost of the members comprising a handle and guide, the intermediate and innermost two members being relatively movable and also longitudinally movable relative to the outermost member, the three members being incapable of axial rotation, a U-shaped magnetic core magnetically insulated from and carried by each of the said intermediate and innermost members, each core having a pole face, the pole faces of the cores confronting each other, a coil carried by each core in symmetrical relation, a current supply for one coil, and an indicator device in series with the other coil, the coils having a primary-secondary circuit relationship.

9. A micrometer as defined by claim 8 where-in each core comprises a pair of substantially parallel arms and each core is mounted by one arm thereof.

10. A micrometer as defined by claim 9 where-in the coils are mounted on the other arms of the cores.

11. A micrometer as defined by claim 8 where-in the cores are of laminated character, the current supply is of alternating current type, the indicator device is of direct current type, and a rectifier is in series with said device.
